W. A. PERVIER

SYRINGE

Filed Aug. 11, 1921

UNITED STATES PATENT OFFICE.

WILLIAM A. PERVIER, OF ALLSTON, MASSACHUSETTS, ASSIGNOR TO CHARLES E. PARKHURST, OF SOMERVILLE, MASSACHUSETTS.

SYRINGE.

Application filed August 11, 1921. Serial No. 491,599.

To all whom it may concern:

Be it known that I, WILLIAM A. PERVIER, a citizen of the United States of America, and resident of Allston, in the county of 5 Suffolk and State of Massachusetts, have invented new and useful Improvements in Syringes, of which the following is a specification.

This invention relates to syringes, and in 10 particular to that type of syringe used in dental and surgical work for flushing or cleansing a cavity or wound with warm water, or with an antiseptic or medicinal solution.

15 For example, in filling teeth it is necessary frequently during the drilling of a cavity for the dentist to ascertain the progress of the work. This is accomplished by cleansing the cavity of particles produced 20 by the drilling by flushing or syringing the same with warm water. The common appliance for this purpose, namely a small bulb syringe, has several serious defects. The dentist must attend to the filling of the 25 syringe by immersing the nozzle in warm water and wait for the collapsed bulb to fill by suction. The water is ejected from the syringe by squeezing the bulb and this act often displaces the nozzle so that the 30 stream is not properly directed, necessitating a refilling of the syringe. The bulb by reason of constant flexing soon develops 35 cracks and leaks and must be frequently renewed. The bulb syringe is consequently a source of annoyance and delay to the dentist in his work.

40 Objects of the present invention are to produce a syringe which can be used continuously without refilling, to provide fluid at a constant temperature near the nozzle of the syringe, to positively control the force and flow of the stream from the syringe, to provide means for gripping and holding the syringe to insure the proper 45 directing of the stream, and in general to overcome the defects of previous devices of this kind.

The invention comprises a fluid chamber 50 with a fluid inlet thereto and two outlets, one of which communicates with a nozzle. The fluid chamber may be enlarged to provide a reservoir in which case the outlet not connected to the nozzle becomes an overflow. The invention is further characterized

by selective means for diverting the fluid 55 from one outlet to the other and for controlling the force and the amount of flow through the nozzle.

In order to illustrate the invention, one 60 concrete embodiment thereof is shown in the accompanying drawings, in which,

Fig. 1 is an elevational view of the device as attached to a dentist's cuspidor when not in use;

Fig. 2 is an enlarged elevational view of 65 the syringe proper;

Fig. 3 is an enlarged view of the syringe and its connections with portions cut away and the syringe itself shown in section; and

Fig. 4 is a perspective view of the washer 70 used in the syringe valve.

The particular embodiment of the invention shown for the purpose of illustration comprises (Fig. 1) a fluid chamber or reservoir 5 with a feed pipe 6 and overflow pipe 7 attached thereto. The overflow pipe 7 is connected to a support 8, comprising a bent metal pipe adapted to hook over the edge of the ordinary dentist's cuspidor 9 (Fig. 3). Attached to support 8 at 10 are 75 wing plates 11 shaped to fit to the sides of the cuspidor bowl. Above wing plates 11 is a double pronged hook 12 upon which the syringe proper is hung as shown in Fig. 1 when the device is not in use.

Receptacle 5 serves as a handle for the device and for this purpose is knurled at certain portions of its exterior as indicated at 80 13 to give a firm grip when held in the hand. The base 14 of the reservoir 5 has an inlet

85 tube 15 fastened in its base to which the flexible rubber pipe 6 is attached. Within the reservoir at the top is a hollow member 16 having a hole 17 as an overflow for the liquid in the reservoir, which is conducted 90 away by pipe 18 extending down through the center of the receptacle and out through the bottom 14 for connection with flexible rubber pipe 7. The receptacle is closed at the top by a screw threaded cap 19 having 95 a ring 20 for suspending the device when not in use from the hook 12 on the cuspidor bowl.

100 Since the liquid to be used in this device is warm water, a continuous flow of the same is necessary to prevent the liquid in receptacle 5 from becoming cold. Pipe 6 is to be connected to any suitable source of warm

water (not shown) and a continuous flow into receptacle 5, and out through overflow opening 17, pipes 18 and 7, is maintained.

Suitable means for taking the liquid from reservoir 5 in any desired quantity and with any desired force may comprise the valve arrangement shown in detail in Fig. 3. Diametrically opposite overflow 17 is an opening 21 in the reservoir for the reception of a tubular member 22 having annular flanges or collars 23 and 24 thereon. Flange 23 abuts against reservoir 5 and determines the extent that member 22 projects within the receptacle. A similar tubular member 26 has a reduced portion 27 telescoping within member 22. A cap nut 28 is screwed upon the end of the reduced portion 27 of slideable member 26 closing the bore thereof and acting as a stop member to prevent the separation of telescoping members 22 and 26. An elongate washer 29 is looped over stop 28, one end receiving the reduced end of slide 26 through hole 30 and the other end receiving in hole 31 the nipple 32 upon stop nut 28.

Near the outer end of telescoping member 26 are annular flanges or collars 33 and 34, similar to flanges 23 and 24 on member 22. Surrounding telescoping members 22 and 26 and held between flanges 24 and 34 thereon is an elastic tube 35, preferably of rubber, for preventing leakage. Surrounding tube 35 and confined between flanges 23 and 33 is a coil spring 36 normally forcing members 22 and 26 apart and holding stop nut 28 pressing one end of washer 29 tightly against the inner end of member 22. Attached to slideable member 26 and abutting flange 33 on the side opposite the spring 36 is an actuator 25 adapted to be encircled by the forefinger of the operator for controlling the valve mechanism.

The extreme outer end of slideable member 27 is screw threaded to receive a union nut 37 for attaching nozzles of various kinds. In the device illustrated, the union nut presses an extension 38 against a washer 39 interposed between the extension 38 and the slideable member 26. If desired, separate nozzle tips such as 40 may be connected to extension 38 by screwing the same upon the threaded end of extension 38, suitable packing being interposed as indicated at 41 to prevent leakage. An annular cup shaped member 42 may be used to retain the packing 41.

The operation of the device is as follows: The device when not in use is hung upon the edge of the cuspidor bowl, as previously described, with liquid flowing continuously into and out of the reservoir 5 which is thus kept full at all times. When the operator wishes to use the device, he grasps the reservoir 5 in his hand extending his forefinger over the actuator 25. This pistol grip arrangement affords

means for holding the device steady while in use and permits very fine graduations of the stream sent through the nozzle. When the actuator 25 is drawn back toward the reservoir 5 member 26 slides through member 22 compressing elastic tube 35 and spring 36. Just as the nipple 32 enters the overflow opening 17, a hole 43 opening into the bore of member 26 is uncovered, permitting water to pass through member 26 and out through nozzle 40. As the actuator 25 is pulled back farther, more and more of the hole 43 is uncovered and the overflow opening 17 is proportionally closed by nipple 32. When the slide member 26 is drawn back to its extreme limit, hole 43 is completely within reservoir 5 taking the full flow of liquid while overflow opening 17 is completely closed, the inner fold of washer 29 being pressed tightly between hollow member 16 and cap nut 28. When actuator 25 is released, spring 30 forces slide member 26 to the other extreme position and the outlet to the nozzle is again tightly closed as heretofore described.

By properly manipulating slide 26 through actuator 25 very fine graduations of the amount of liquid diverted through the nozzle are possible, particularly if the hole is made somewhat elongate as in the form of a slot. The force of the stream is controlled in a similar manner since the bore of the nozzle is much smaller than the inlet to the receptacle. When the hole 43 is so arranged as to be completely within the receptacle before the nipple enters opening 17, only a slow trickle or drip occurs at the tip of the nozzle since the pressure of the inflowing liquid is relieved by the overflow. The flow from the nozzle can be increased by degrees to a powerful jet by gradually closing the overflow opening 17 as the member 26 is drawn inwardly by actuator 25.

I claim:

1. A syringe comprising a fluid chamber forming a hand grip, a nozzle supported by and communicating with the chamber, a normally open outlet, and selective means for diverting fluid from said outlet to said nozzle.

2. A syringe comprising a fluid chamber forming a hand grip, a nozzle supported by and communicating with the chamber, means continuously passing liquid through said chamber, and means for selectively diverting liquid from its course through the chamber to said nozzle.

3. A syringe having a reservoir, means for continuously passing liquid through the reservoir comprising an inlet and an outlet, and valve means comprising a slideable nozzle for selectively diverting through said nozzle any desired quantity of said liquid.

4. A syringe having a reservoir, an intake and an overflow for said reservoir, said res-

ervoir having an opening opposite said overflow, and means movable through said opening for closing said overflow.

5. A syringe having a reservoir, an inlet for liquid, an overflow, said reservoir having an opening opposite said overflow, and a hollow member movable through said opening for closing said overflow and simultaneously conducting the liquid from said

10 reservoir.

6. A syringe having a reservoir, an inlet for liquid, an overflow, said reservoir having an opening opposite said overflow, and a member movable through said opening 15 having means thereon for closing the overflow and the opening respectively when the member is in its extreme inner and outer positions.

7. A syringe having a reservoir, a liquid 20 intake and an overflow therefor, said reservoir having an opening opposite said overflow, a tubular member fast in said opening, a hollow member having a reduced portion slideable in said tubular member, a flexible elastic tube surrounding adjacent portions of both said members to prevent leakage, a stop on said hollow member within the reservoir, said hollow member having a hole connecting with its hollow interior adjacent said stop, a spring surrounding said tube and bearing against both said members for normally maintaining said hole out of contact with the liquid in the reservoir, a nozzle attached to said slideable member, 35 and means on said slideable member for drawing the latter inwardly whereby said stop will cut off said overflow and said hole will come within the reservoir to direct a stream of liquid through said nozzle.

40 8. A syringe having a reservoir, an overflow therefor, said reservoir having an opening opposite said overflow, a member movable through said opening having a stop thereon within said reservoir, a washer 45 looped over said stop whereby the liquid in said reservoir is completely shut off at said overflow or at said opening when said slideable member reaches the extreme limit of its movement in each direction.

50 9. A syringe having a reservoir, an intake and an overflow therefor for maintaining the reservoir full of liquid at all times, a nozzle, and means for regulating the flow of liquid through the nozzle and for proportionately cutting off the overflow from the reservoir.

55 10. A syringe having a fluid chamber, an inlet for liquid, two outlets therefor, and

means for proportionately closing one outlet as the other is opened.

60 11. A syringe having a fluid chamber, an inlet for liquid, two outlets therefor and means normally closing one of said outlets and adapted to proportionately close the other outlet as the first outlet is opened.

65 12. A syringe having a fluid chamber, an inlet for liquid, two outlets therefor, and means slideable in one outlet normally closing the same and adapted to proportionately close the other outlet as the first outlet is opened.

70 13. A syringe having a fluid chamber, a nozzle communicating therewith through a valve comprising tubular telescoping members, collars thereon, means surrounding said members between said collars to prevent leakage, and yielding means tending to separate said members to keep the valve normally closed.

75 14. A syringe having a fluid chamber, a nozzle communicating therewith through a valve comprising tubular telescoping members, collars thereon, an elastic tube surrounding said members between certain of said collars to prevent leakage, and a coil spring surrounding said elastic tube and confined between the other collars on said telescoping members to keep the valve normally closed.

80 15. A syringe having a fluid chamber and a nozzle communicating therewith through a valve comprising telescoping members having a passage therethrough, means preventing the separation of said members, means opposing relative movement of said members including a rubber tube engaging both of said members to prevent leakage therebetween, and means whereby said members may be moved relatively to each other to permit liquid to pass and to control the force and the amount of fluid passing therethrough.

85 16. A syringe having a fluid chamber, an inlet to said chamber and two outlets therefrom, valves for controlling said outlets and means to open or close one valve as the other is closed or opened.

90 100 17. A syringe having a fluid chamber, an inlet to said chamber and two outlets therefrom, valves for controlling said outlets and means including a manual actuator simultaneously to open or close one valve as the other is closed or opened.

95 Signed by me at Boston, Massachusetts, this 6th day of August, 1921.

110 WILLIAM A. PERVIER.
